BOX WRENCH CLIP

Nellie Thompson, Los Angeles, Calif.

Application March 22, 1943, Serial No. 479,965

5 Claims. (Cl. 81—125)

My invention relates to a simple attachment for a box wrench, whereby the box wrench will be equipped with means to frictionally engage a nut or screw or bolt head which is placed in the opening of the wrench.

Herein the term "box wrench" is employed to designate a wrench having an annular or cylindrical wall having therein or therethrough a nut receiving opening defined by a plurality of flutes or channels to receive the lateral corners of the nut, the number of such flutes or channels being a multiple of the number of lateral corners on the nut. For example, a box wrench for a hexagonal nut or hexagonal head of a machine screw has twelve flutes and accordingly only six of such flutes are engaged at any one time by the corners of a hexagonal nut, the remaining flutes being disposed adjacent the central portion of the side faces of the nut.

It is an object of the present invention to provide a simple and inexpensive clip which may be readily stamped from sheet metal, this clip having slender members positioned so as to lie in unoccupied flutes of a box wrench opening, with at least one of these slender members frictionally engaging a side face of the nut so as to hold the nut in the opening. Throughout this specification it will be understood that the term "nut" means not only a body which is movable on a screw in response to rotation, by reason of the threaded engagement of such body with the screw, but also any nut-like body which may be fixed on the stem of a screw, for example, the hexagonal head of a machine screw. This understanding is advanced for the reason that the box wrench, with my clip therein, is ordinarily used on the nuts and heads of bolts.

It is a further object of the invention to provide a box wrench clip comprising a frame or supporting structure and fingers extending from this supporting structure so as to lie in planes which radiate from the center of the supporting structure and are disposed at such angles that the fingers will lie in flutes of the opening of a box wrench.

A further object of the invention is to provide a box wrench clip of the character set forth in the preceding paragraph, wherein the fingers have extending portions arranged to lie against the front face of the box wrench and bend rearward over the outer face to frictionally engage the same, whereby the clip will be held in operative position.

In the preferred practice of the invention the frame of the clip is of such size that it will pass

10 through the opening of the box wrench, or within the same, to a position spaced from the front face of the wrench. A further object of the invention is to provide a clip for a box wrench, this clip having fingers to lie in flutes of the box wrench opening, and a supporting frame connected to like ends of the fingers, which supporting frame will serve as a stop to limit axial movement of a nut in the opening of the box wrench.

15 Further objects and advantages of the invention will be understood from the following specification, and the drawing which is referred to therein.

15 Referring to the drawing which is for illustrative purposes only,

Fig. 1 is a face view of a stamping for a preferred form of my box wrench clip.

20 Fig. 2 is a side view of a box wrench having therein a clip embodying my invention.

Fig. 3 is an enlarged fragmentary view taken from the position indicated by the arrow 3 of Fig. 2.

25 Fig. 4 is a sectional view taken as indicated by the line 4—4 of Fig. 3.

Fig. 5 is a sectional view similar to Fig. 4, with the nut removed from the box wrench opening.

The stamping 10, shown in Fig. 1, includes a frame or supporting structure 11, from which slender members 12 radiate, these slender members 12 being occasionally referred to as fingers. The stamping 10 is for a clip to be used in a box wrench for hexagonal nuts, and, accordingly, the fingers 12 are disposed at angles α of 35 120° . The frame 11 is of such peripheral size that it will pass through or within the opening of a box wrench in which the clip is used. As shown in the remaining figures of the drawing, and especially the enlarged sectional view, Fig. 5, the frame 11 is disposed contiguous to the rear face 13 of the box wrench 14. The fingers 12 are bent with relation to the frame 11 so as to lie substantially perpendicular thereto and to extend forward in unoccupied flutes 15 of the box wrench 14. As clearly shown in Fig. 3, the fingers 12 are of such shape and cross sectional area that they will be received within the unoccupied flutes 15 and will lie adjacent the faces 16 which form the sides of a nut 17 disposed in the opening of the box wrench.

40 The intermediate portions 18 of the fingers 12 are bent outwardly so as to extend across the front face 20 of the box wrench 14, and the end portions 21 of the fingers 12 are then bent rearward from the intermediate portions 18 so as to

lie across the outer face 22 of the box wrench. Preferably the end portions 21 of the fingers 12 conform relatively closely to the outer face 22 of the box wrench 14 so as to provide a frictional engagement therewith which will contribute to holding of the clip 23 in position in the box wrench opening. As shown at 25 in Fig. 5, at least one of the fingers 12 may be bowed inward slightly for frictional engagement with a side face of the nut 17. Also, the frame 11 defines an opening 26 of such size that a screw 27 may pass therethrough, as shown in Fig. 4.

The box wrench 14 is normally equipped with means to hold or rotate the same. It will be understood that such holding or rotating means may, in accordance with standard wrench practice, extend axially, after the fashion of a socket wrench, or such means may consist of a radial handle 28, as shown in Fig. 2.

A nut 17, when placed in the opening of the socket wrench, as shown in Figs. 2, 3, and 4, will be frictionally held as the result of the presence of the clip 23, and also the frame 11 will serve as a stop to limit movement of the nut 17 in rearward direction. Accordingly, the nut 17 will be held in the opening of the box wrench 14 with the face 30 thereof contiguous to the front face 20 of the box wrench, and preferably protruding slightly, as shown in Fig. 4. It is sometimes found that the head of a machine screw is inaccessible to a workman when he is positioned so as to operate a wrench on a nut threaded on the screw. My invention makes it possible to apply a box wrench to the head of the screw, where it will be frictionally held and will rotate with the screw until it engages a projection which will serve as a stop, this making it possible for a workman to give his attention to the tightening of a nut on the accessible end of a screw. A particular advantage of my simple clip is that it will securely hold a nut within the opening of a box wrench so that the wrench may then be employed as the means for holding and applying the nut to the screw.

I claim as my invention:

1. In a clip for a hex-nut box or socket wrench having twelve similar flutes, the combination of: a frame of a size to pass through the opening of the wrench and occupy a position spaced backward from the front end of the opening; and fingers projecting from said frame in planes which radiate from the center of said frame at angles which are a multiple of 60° , said fingers being relatively narrow to lie in flutes of the wrench opening not occupied by corners of a hexagonal nut received in said opening, with the outer portions of said fingers being shaped like hooks and extending over the front face of the wrench and then down over the external side face of said wrench, the portion of at least one of said fingers which lies in said flutes frictionally engaging the nut which is placed in the opening of the wrench.

2. In a clip for a box or socket wrench having similar flutes, the number of which is a multiple of the number of corners of the nut for which the

wrench is intended, the combination of: a frame of a size to pass through the opening of the wrench and occupy a position spaced backward from the front end of the opening; and fingers projecting from said frame in planes which radiate from the center of said frame and being relatively narrow to lie in flutes of the wrench opening not occupied by corners of a nut received in said opening, with the outer portions of said fingers being bent outward so as to extend over the front face of said wrench, the portion of at least one of said fingers which lies in said flutes frictionally engaging the nut which is placed in the opening of the wrench.

3. In a clip for a box or socket wrench having a plurality of flutes adapted to receive corners of a nut, the number of said flutes being a multiple of the number of corners of the nut for which the wrench is intended, the combination of: a frame of a size to pass through the opening of the wrench and occupy a position spaced backward from the front end of the opening, said frame having a wall positioned so as to engage an end face of the nut; and fingers projecting from said frame in planes which radiate from the center of said frame and which are relatively narrow so as to lie substantially wholly in flutes of the wrench opening not occupied by corners of a nut received in said opening, the portion of at least one of said fingers which lies in one of said flutes frictionally engaging the nut which is placed in the opening of the wrench.

4. In a clip for a box or socket wrench having a plurality of flutes adapted to receive corners of a nut, the number of said flutes being a multiple of the number of corners of the nut for which the wrench is intended, the combination of: a plurality of slender members disposed so as to extend respectively in flutes of the opening of said wrench not occupied by the corners of a nut placed in said opening, and supporting means connected to like ends of said resilient members so as to hold them in place in said flutes, said supporting means having a transverse wall positioned so as to engage an end face of the nut, and said members being so formed that at least one of them will frictionally engage the nut placed in said opening.

5. In a clip for a box or socket wrench having a plurality of flutes adapted to receive corners of a nut, the number of said flutes being a multiple of the number of corners of the nut for which the wrench is intended, the combination of: a plurality of slender members disposed so as to extend respectively in flutes of the opening of said box wrench not occupied by the corners of a nut placed in said opening, and supporting means connected to like ends of said members so as to hold them in place in said flutes, said supporting means comprising a thin flat wall lying in a plane substantially normal to the axis of the wrench opening, said members being so formed that at least one of them will frictionally engage the nut placed in said opening.

NELLIE THOMPSON.
